UNITED STATES PATENT OFFICE

BENJAMIN J. MANCUSO, OF BATAVIA, NEW YORK

COLD AIR BOOT

Application filed December 29, 1933. Serial No. 329,171.

This invention has reference to a hot air furnace, and more particularly to a novel cold air boot for conducting cold air into the furnace casing.

5 The advantages of the invention are as follows:

First, it saves labor and material;

Second, it can be installed in a minimum of time and it occupies but a minimum of 10 space; and,

Third, it eliminates the use of elbows, thus providing for less friction and better circulation.

15 With the above and other objects in view, the invention consists in the novel construction and arrangement of parts hereinafter more fully described and illustrated in the accompanying drawing, wherein:

20 Figure 1 is a side elevation of a furnace embodying the invention, the furnace casing being partly in section to show the manner in which the cold air boot is attached thereto; and,

25 Figure 2 is an end view of the furnace.

Describing the invention in detail, 10 designates a hot air furnace of the usual and ordinary construction provided with the customary casing 11 which, for purposes of the present invention, has an air inlet 30 opening 12 on one side and at a point adjacent the bottom, as illustrated.

Attached to the casing 11, over the inlet 12, is a cold air boot 13 forming the subject matter of the present invention.

35 This cold air boot is preferably formed of galvanized iron, though other suitable material may be used, if desired, and is of a box-like configuration, open on the side adjacent the furnace casing, which open side 40 is flanged, as shown at 14, for attachment to the casing. The boot has a greater cross area at the top than at the bottom, being approximately 20" at its widest part, as indicated at 15, and approximately 10" at

45 its base 16, the rear wall 17 of the boot being disposed on a slant, as shown. The top wall 18 of the boot is disposed approximately on a 45 degree angle and is provided with an opening 19 surrounded by an upstanding flange or collar 20, over which engages an

end of the cold air pipe 21, which has its other end located in the floor 22 of the building or dwelling. The cold air which enters pipe 21 is conducted by way of the cold air boot into the furnace casing through the opening 12, and circulates around the furnace so as to be heated, the heated air being supplied through one or more air ducts to the rooms which are to be heated.

55 The cold air boot fits closely against the casing, extending upwardly along the side of the casing for an appreciable distance, being approximately four feet high, and, as will be observed from the drawing, it occupies but little space in comparison with other forms of cold air inlets heretofore employed in connection with hot air furnaces, and it enables the use of shorter and more direct air ducts, such as shown at 21, 60 for conducting cold air into the furnace casing, thereby doing away with elbows commonly used in other methods, with the result that the air passes into the furnace casing with less friction and better 65 circulation.

70 Various changes in the form, proportions and minor details of the invention may be made within the scope of the appended 75 claims.

Having thus described the invention, what 80 is claimed is:

1. A cold air boot for hot air furnaces, comprising a metallic box-like member of greater cross area at the top than at the bottom, and having a flanged open side for attachment to a furnace casing, said boot having an air inlet at the top disposed in a plane inclined with respect to the horizontal.

85 2. A cold air boot for hot air furnaces, comprising a tapering box-like member presenting greater cross area at the top than at the bottom, and having a flanged open side for attachment to a furnace casing, the top wall of said boot being inclined at a 45 degree angle to the horizontal, and having a flanged air inlet opening for engagement with a cold air pipe.

90 3. A cold air boot for a furnace-enclosing casing having a cold air inlet adjacent its 95

base, comprising an elongated casing having a flanged open side adapted to be secured vertically of the casing with its lower end disposed over the said cold air inlet of the latter, said casing having an outwardly and downwardly sloping top wall presenting a flanged air inlet opening for attachment thereto of a cold air pipe and being of such tapered construction that the horizontal cross sectional area of the boot diminishes as it approaches the lower end thereof and the vertical cross sectional area diminishes outward.

4. In a warm air furnace, the combination of a casing with intake openings for

cold air at the lower part, a cold air box connection for each cold air intake opening formed of walls on three sides secured to the furnace casing and one side formed by the furnace casing, and a pipe joint connection at the top of said cold air box and a cold air pipe connected thereto.

5. In a warm air furnace, the combination of a casing, an aperture in the lower part of the casing, and a cold air box with walls at three sides and with the casing wall constituting one side thereof and adapted to deliver air to the said aperture and a cold air pipe connected thereto.
